UNITED STATES PATENT OFFICE.

CHARLES C. CHAPPELLE, OF NEW YORK, N. Y.

GAS-BURNER.

1,353,217.

Specification of Letters Patent. Patented Sept. 21, 1920.

Application filed July 11, 1918. Serial No. 244,375.

To all whom it may concern:

Be it known that I, CHARLES C. CHAPPELLE, a citizen of the United States, residing at New York city, in the county of New York and State of New York, have invented certain new and useful Improvements in Gas-Burners, of which the following is a specification.

This invention relates broadly to gas burners and more particularly to a gas burner for furnishing a pilot light or the like.

The principal object of the present invention is to produce a gas burner for burning a small round flame or pencil flame, and wherein the burner is so constructed that the gases producing the flame are protected to prevent the flame from being blown out.

A still further object of the present invention is a gas burner of the character specified wherein a stream of gas is directed through a minute opening which is surrounded by inlets for air in such manner that the stream of gas is projected through an envelop of air drawn with the stream of gas due to the velocity of the gas stream.

A still further object of the present invention is a gas burner as specified wherein the air inlets are arranged around the base of a cylindrical shield and with a second shield arranged around the air openings whereby a pair of concentric shields are provided.

More specifically one object of the present invention is a pilot light as stated, wherein a minute stream of gas is projected through a cylindrical sleeve inclosing an envelop of air and with an air pocket arranged adjacent the supply for the said air envelop in such manner that drafts or gusts of wind cannot extinguish the flame.

A still further and more specific object of the present invention is a gas burner as specified wherein the burner tip is constructed to project a minute stream of gas through a hollow cylinder provided with openings in the base thereof adjacent the exit for the gas and wherein these openings in the cylinder lead to an annular pocket surrounding the burner tip in such manner as to prevent drafts or gusts of air from flowing past the base of the burner tip and to maintain the air pressure within the burner tip and around the base of the burner tip at substantially the same pressure.

Other and further objects of this invention will in part be obvious and will in part

be pointed out hereinafter in the specification following by reference to the accompanying drawings wherein like parts are designated by like characters throughout the several figures thereof.

Figure 1 is a sectional view showing the burner mounted on the end of a suitable gas supply pipe.

Fig. 2 is a detail view showing a portion of the burner in section and diagrammatically illustrating the effect of a blast of air blowing directly into the tip.

Fig. 3 is a more or less diagrammatic view illustrating the burner operating as a pilot light for lighting the burners in an automatic gas water heater.

Burner tips for producing pencil gas flames are old in the art and are adapted for use where a small auxiliary gas flame is desired or where heat is intended to be applied locally; such as pilot lights, cigar lighters, or welding flames and the like. Such flames have heretofore in the art been produced by projecting a small gas flame into atmosphere. For certain types of combustible gases, for example, acetylene, burner tips

have been provided wherein the gas is projected through a short pocket provided with openings to lead air around the stream of gas. Such burners are adapted more specially for use in protected places such as lamps for automobiles or the like, and are not well adapted for use in open air and without protection because a blast of air blowing directly against a stream of gas will pass through the air openings with such velocity as to "blow out" the gas unless the gas is issuing under heavy pressure. One of the difficulties with pilot lights, cigar lighters, and the like is the fact that necessarily the gas issuing through the burner tip must issue at a low pressure and therefore, such lights are liable to be extinguished by drafts.

The extinguishing of a pilot light usually is more or less serious because the object of the pilot lights is to insure igniting a main burner which normally is not in operation. One common use for pilot lights is in the burner chamber for automatic gas water heaters wherein when water is turned on at a service tap a large flow of gas is admitted to heating burners which are adapted to be ignited by a pilot flame. In all cases such ignition is substantially an explosion for the reason that the burners and the burner chamber normally is full of air and when

the flow of gas comes on it produces an explosive mixture which ignites when it reaches the pilot flame. The burner chamber is usually more or less inclosed and the explosion produces a blast of air which travels outwardly from the burners. This blast occasionally blows out the ordinary pilot burner and since the pilot burner is spaced away from the main burners a sufficient distance to prevent its being burned up when the main burners are in full operation, it sometimes happens that the pilot light is not relighted by the main burners so that when the water is turned off there is no pilot light. 10 When the water is again turned on the flow of gas completely fills the water heater and escaping into the room may be ignited by a spark from an electric bell or some other agency and a serious explosion results. 15 When the present invention is so constructed that the pilot light flame cannot be "blown out" by such explosions as have been described since the velocity of the air moving past the burner tip is transformed into pressure adjacent and around the out flowing stream of gas in such manner that the blast is neutralized. 20

Referring now to the drawing and more especially to Fig. 1, the burner tip A comprises a protecting shield 1 which preferably is conical on the exterior and cylindrical on the interior to form a straight walled cup. A plurality of air inlet openings 2 are provided adjacent the base of the shield 1 and 30 which have their axes inclined toward the gas orifice 3, in such manner as to intersect the axis of the gas orifice within the cup formed by the shield 1. While various sized orifices may be used I prefer that the diameter thereof shall be approximately thirteen one-thousandths of an inch, which is so small that the amount of illuminating gas normally passing therethrough will not operate the ordinary consumer's gas meter. 40 Another and an important reason for choosing the above diameter for the orifice is the fact that practice and experiment has shown that under normal consumer's gas pressure an orifice of this size gives a proper flame for a pilot light without throttling down the pressure by a choke valve. Furthermore it has been found that the gas friction on the side walls of an orifice of this size increases at a rate that is greater than the proportionate increase in gas pressure, after the pressure is increased above the normal pressure specified. Therefore such an orifice produces a substantially constant flame under conditions where the ordinary pilot flame 50 would vary greatly. The base of the tip is screw-threaded as at 4 and fits into a tapped opening in the main shield B. This main shield B is provided with an inclined wall 5 that extends around the burner tip in such 60 manner as to provide an annular space 6

around the base of the burner tip. This main shield B is also screw threaded and adapted to fit on the end of a suitable gas pipe 7. A conical screen 8 is provided with a rim 9 adapted to be clamped between the gas pipe 7 and the main shield B with the tip of the screen extending into the gas pipe. The meshes of this screen 8 are of less diameter than the diameter of the gas orifice 3 so that no dust particle will pass through the screen that will not pass out through the orifice, therefore there is no danger of the orifice being clogged. The screen may be very easily cleaned whereas if the orifice were permitted to clog and be cleaned there is liability of the opening being enlarged or of the tip being broken. Preferably a lock nut 10 clamps a gasket washer 11 tightly against the base of the main shield B thereby providing a gas tight joint. While various materials may be used in the making of this gas burner I prefer the tip A and the main shield B shall be constructed of steatite, lava, or the like. 85

In Fig. 3 the device is shown as being used for pilot light for the burners of an automatic water heater wherein the burners 12 are located within the burner chamber 13 beneath the water coils 15 and are supplied through the gas main or pipe 16 which is controlled by an automatic valve 17 as is common in the art. The chemical combination of oxygen of the air and hydrogen of the gas when the main burners are in operation produces a considerable amount of water, which condenses on the cold water coils and falls into the burner chamber as rain. The main shield B thoroughly protects the burner tip A from this rain which might otherwise carry particles, rust, etc., into the burner tip and clog the same. 95

Fig. 2 illustrates the effect of a draft or explosive air wave when driven into the end of the burner and wherein the arrows C indicate the blast of air or wind. It is obvious that such blast cannot flow past the burner tip A but is collected within the annular space 6 between the main shield B and the tip A in such manner that the pressure in this annular space 6 is equalized with the pressure within the cup of the shield 1 so that there can be no violent rush of air through the openings 2 counter to the gas stream, to extinguish the flame. It will be noted the cup in the shield 1 of the tip A is cylindrical or straight walled, while the cup in the shield B is conical, diminishing toward the base of the cup. When a gust of wind or an air wave due to gas explosion is driven into this burner there is a tendency of a higher pressure to form in the space 6, due to the converging walls of the cup in the shield B, than the pressure in the cylindrical walled cup in A. The next tendency is to equalize the pressure by the air flowing 110 115 120 125 130

from the cup in B to the cup in A through the air ports 2, with the flow in the same direction as the gas flow. Because of these facts the flame cannot be "blown out" by 5 gusts or drafts or air. Another and important effect of the shield 1 of the burner tip is to heat and direct the air coming in contact with the stream of gas D in such manner that the greatest zone of heat of the 10 flame is directly in line with the flame itself and not above or at one side of the flame. This fact renders the present tip especially adaptable to cigar lighters, welding, etc., where the heat is to be directed on a definite 15 spot.

Since the present invention might be carried out in structures other than that specifically disclosed herewith I desire it to be understood that the specific constructions described and shown are to be understood as 20 illustrative and not to be taken in the limiting sense.

I claim:

1. A gas burner comprising a burner tip 25 provided with a minute gas orifice, a shield extending beyond said gas orifice and comprising a small cylindrical walled cup through which the gas from said gas orifice issues, said tip being provided with air inlet 30 openings adjacent the said shield, and a main shield surrounding the base of said tip to comprise a large cup surrounding the base of said tip, the walls of said large cup being tapered inwardly in such manner that there 35 is a tendency for gusts of wind to create a pressure in this cup in excess to pressure in the small cup whereby the flame is prevented from being extinguished.

2. A gas burner comprising a burner tip 40 provided with a gas orifice, a shield surrounding said orifice extending outwardly therefrom, said burner tip being provided with air inlet openings adjacent the base of said shield, the exterior of said shield comprising the frustum of a cone, and the under 45 portion of said tip being cut away, in combination with a conical walled cup surrounding the base of said burner tip and a portion of the conical part of said tip whereby an 50 annular chamber is formed adjacent to said air inlet openings to provide a reservoir from which air is supplied to the gas stream projected through the first mentioned shield.

3. As an article of manufacture a gas 55 burner comprising in combination a burner tip having a single minute orifice, a cup extending outwardly from said orifice and through which the gas from said orifice is adapted to be projected, air inlet openings 60 in the bottom of said cup and adjacent said orifice with the axes of said inlet openings inclined toward the axis of said orifice, in combination with an inclined walled cup member surrounding the base of said tip 65 and protecting said air inlet openings in

such manner that gusts of air are pocketed adjacent the said air inlet openings and the velocity of said gusts is reduced to pressure substantially as specified.

4. In a gas burner the combination of a 70 burner tip provided with a minute gas orifice, said burner tip being provided with a substantially cylindrical cup the axis of which is substantially the same as the axis of the orifice, said tip being provided with 75 air openings the axis of which are inclined toward the axis of said orifice whereby air drawn through said openings moves toward said orifice, and a shield around the base of said tip to protect the said air inlet 80 openings.

5. A gas burner comprising a burner tip being provided with a minute orifice, a shield extending from said orifice and comprising a small cylindrical cup through 85 which gas from said orifice is directed, said burner tip being provided with air inlet openings adjacent said orifice, and an inclined walled cup surrounding the base of said burner tip. 90

6. A gas burner comprising in combination a burner tip, a shield surrounding said burner tip, said burner tip being provided with apertures opening adjacent the base of said shield and in front of the tip orifice and adapted to admit air to surround a stream 95 of gas issuing from the orifice of said burner tip, protecting means surrounding said burner tip and protecting said air openings from lateral air currents, and a compression 100 cup effective to accelerate the discharge through said openings.

7. In a gas burner the combination of a burner tip comprising a body portion, a cup shaped shield extending forwardly from 105 said body portion, said tip being provided with forwardly directed air inlet channels extending into the base of said cup and opening ahead of the tip orifice, and an annular shield surrounding and protecting 110 said openings.

8. A gas burner comprising a burner tip provided with an orifice located on the axis thereof, a shield surrounding and extending forwardly beyond said orifice and open at 115 its forward extremity, and a compression cup associated with said shield and having a front opening, the area of which is greater than the area of the shield opening, there being channels affording access from the 120 compression cup to the interior of the shield at the rear portion of the latter.

9. A gas burner comprising a burner tip provided with a forwardly directed orifice, a shield surrounding said orifice and extending forwardly therefrom, and a cup encircling the shield and having a front opening of greater area than the front opening of the shield, there being provided a plurality of forwardly directed air inlet open- 125 130

ings affording communication between the interior of the cup and the interior of the shield and terminating ahead of the orifice to surround the stream of gas from the orifice with a traveling envelop of air in such manner as to maintain the flame separated from the shield.

10. As an article of manufacture, a gas burner comprising in combination a burner tip formed as a cup and provided with a minute gas orifice in its bottom and a mouth in front of the orifice through which the gas from said orifice is projected, a screen behind the orifice through which the gas is 15 fed to the orifice, forwardly directed open-

ings through the side of the cup in front of the orifice, and means for directing air currents through said openings.

11. A gas burner comprising a burner tip provided with a gas discharge orifice, an inner shield surrounding and extending forwardly from said orifice, there being passages to introduce air into said shield adjacent said orifice, in combination with an outer shield encircling the portion of the burner containing said passages, and providing a cavity between the inner and outer shields; said cavity decreasing in cross-sectional area from the front orifice thereof.

CHARLES C. CHAPPELLE
